UNITED STATES PATENT OFFICE

150,567

DESIGN FOR A VEHICLE BODY

James W. Greig, Detroit, Mich., assignor to Wood-all Industries Incorporated, Detroit, Mich., a corporation of Michigan

Application January 31, 1947, Serial No. 136,576

Term of patent 7 years

(Cl. D14—3)

To all whom it may concern:

Be it known that I, James W. Greig, a citizen of the United States of America, residing at Detroit, in the county of Wayne and State of Michigan, have invented a new, original, and ornamental Design for a Vehicle Body, of which the following is a specification, reference being had to the accompanying drawing, forming part thereof.

The figures of the drawing are as follows:

Fig. 1 of the drawing is a perspective view of my new vehicle body looking at it toward the front end and toward one side.

Fig. 2 is a perspective view thereof looking at

the opposite side and toward the rear. The dotted line showing in the drawing figures is for illustrative purposes only.

I claim:

The ornamental design for a vehicle body, as shown and described.

JAMES W. GREIG.
